UNITED STATES PATENT OFFICE.

CHARLES EDWIN FIELDS, OF PORTLAND, MAINE, ASSIGNOR TO THE E. T. BURROWES COMPANY, OF PORTLAND, MAINE, A CORPORATION OF MAINE.

FOLDING TABLE.

Application filed April 2, 1926. Serial No. 99,238.

This invention relates to improvements in light, portable, folding tables of the type commonly employed for card tables and like purposes.

5 The object of the invention is to provide improved leg attaching and top supporting means for tables of the kind referred to whereby efficient pivotal connections for the legs are afforded and a simple, strong, firm 10 construction is provided which can be easily assembled and can be produced at low cost.

The invention, with other objects and advantages thereof, and the particular construction, combination and arrangement of 15 parts comprising the same, will be understood from the hereinafter contained detail description, when considered in connection with the accompanying drawings, forming part hereof, and illustrating one embodiment 20 of the invention.

In the drawings:

Figure 1 is a bottom plan view of a table equipped with leg attaching and top supporting and reinforcing means constructed 25 in accordance with the present invention, the legs being in folded position.

Figure 2 is a side elevation, the legs being unfolded.

Figure 3 is a detail section, on an enlarged 30 scale, on the line 3—3 of Figure 1.

The invention comprehends improved leg attaching and top supporting means comprising a fastening member extending from the top supporting frame inwardly thereof and 35 forming a pivot for one of the legs and also engaging an end portion of a cleat or reinforcing strip of the top and serving to hold the same in position to support the top. More particularly the invention contemplates improved 40 leg attaching and top supporting means comprising a bolt extending through an opening in the top supporting frame inwardly of the frame to form a pivot for a leg and overlapping an end portion of a cleat of the top, said means also including a nut on 45 the bolt intermediate the ends thereof to maintain the leg in position on the bolt.

While a specific embodiment of the invention is illustrated in the drawings, it will of 50 course be understood that minor changes and variations may be made in the particular construction shown, and the invention embodied in other forms, as will appeal to those skilled

in the art and falling within the scope of the appended claims, without departing from 55 the spirit of the invention.

Referring to a detail description of the particular embodiment of the invention illustrated in the drawings, the top supporting frame is shown square shaped composed of 60 bars 1 suitably secured together. 2 is a relatively light thin top of paper board or the like secured to the top supporting frame in any suitable way. The top 2 is provided with reinforcing strips or cleats 3 secured thereto 65 at the under side thereof in any suitable manner, as by gluing, said reinforcing strips or cleats extending diagonally within the top supporting frame, the ends of the cleats lying adjacent the corners of the frame. 4 designates the legs pivoted to the top supporting frame adjacent corner portions thereof to fold within the same substantially parallel 70 with and close to the sides of the frame, as shown in Figure 1 of the drawings. 5 and 6 75 are sets of braces for the legs 4.

The improved leg attaching and top supporting means provided in accordance with the present invention comprises fastening members in the form of bolts 7 or the like extending from the top supporting frame adjacent corner portions thereof inwardly within the same, said bolts 7 being of a length to form pivots for the legs 4 and to engage or interfit with an end portion of 85 one of the cleats or reinforcing strips 3 to hold the same in place to support the top 2. Each of the bolts 7, which extend inwardly through openings in the supporting frame, have a smooth portion 7^a to engage the pivot opening in the leg, an intermediate threaded portion 7^b, a nut 7^c to engage said threaded portion to retain the leg in position on the bolt, and an outer end portion 7^d to engage an end portion of one of the cleats 3. 90 In the particular construction shown, the end portions 7^d of the bolts extend in interfitting overlapping relation with end portions of the cleats 3 at the under side thereof, the bolts 7 forming pivots for the legs and also acting to hold the cleats or reinforcing strips 3 in position to firmly support the top 2 inwardly of the top supporting frame. Each of the bolts 7 is provided with means to engage the frame and prevent turning of the same in 100 the bolt opening. For this purpose, in the

construction shown, each bolt 7 is provided with a square shoulder portion 7^g adjacent its head.

It will be noted that the particular leg attaching and top supporting means, hereinbefore described, is of a simple efficient nature. It provides for the firm connection of the legs with the top supporting frame, and for securely holding the cleats or reinforcing strips in place to firmly support the top inwardly of the top supporting frame. The resulting structure is of a simple, strong, rigid character, that can be quickly assembled and produced at low cost.

15 What I claim is:

1. A folding table of the class described, including a top, a rectangular shaped frame supporting the top, reinforcing strips secured to the top and extending diagonally thereof within the supporting frame, legs pivoted to the frame adjacent the corners thereof to fold within the same, and bolts or the like, engaging openings in the top supporting frame adjacent the corners thereof and extending within the same, said bolts or the like forming pivots for the legs, means on the bolts intermediate the ends thereof to maintain the legs in position, and each of said bolts having an end portion extending in overlapping and abutting relation with an end portion of one of the reinforcing strips at the under side thereof.

2. A folding table of the class described, including a top, a rectangular shaped frame supporting the top, reinforcing strips se-

cured to the top and extending diagonally thereof within the supporting frame, legs pivoted to the frame adjacent the corners thereof to fold within the same, and bolts engaging openings in the top supporting frame adjacent the corners thereof and extending within the same, said bolts forming pivots for the legs, and nuts on the bolts intermediate the ends thereof to maintain the legs in position, and each of said bolts having an end portion extending in overlapping and abutting relation with an end portion of one of the reinforcing strips.

3. A table including a top, a frame for supporting the top, a reinforcing strip for the top secured thereto and extending across the same inwardly of the top supporting frame, legs pivoted to the top supporting frame to fold within the same, and leg attaching and top supporting means comprising a bolt or the like engaging an opening in the top supporting frame and supported by said frame, said bolt extending inwardly of the frame through an opening in one of the legs and forming a pivot therefor, and said bolt having its inner end portion extending in overlapping and abutting relation with an end portion of the reinforcing strip to support the top inwardly of the frame, said bolt constituting a supporting connection between the frame and said reinforcing strip.

In testimony whereof I hereunto affix my signature.

CHARLES EDWIN FIELDS.
